FIG. 2

FIG. 3

FIG. 4

FIG. 1 is a side perspective view of a toy trackway, embodying my new design;

FIG. 2 is a top plan view thereof;

FIG. 3 is a side elevational view thereof of either side since the toy trackway is substantially symmetric; and

FIG. 4 is, similarly, an end elevational view from either end.

The characteristic feature of my design resides in the combination of the particular undulating track configuration and the apertured pattern of the bridge portion in conjunction with the track.

I claim:

The ornamental design for a toy trackway, as shown and described.
